REAR WINDOW FOR AUTOMOBILES OR THE LIKE

Frank J. Carson and Herbert A. Leflet, Jr., Toledo, Ohio,
assignors to Libbey-Owens-Ford Glass Company, Toledo, Ohio

Filed Nov. 2, 1960, Ser. No. 62,711

Term of patent 14 years

(Cl. D14—6)

Fig. 1.

Fig. 2.

Fig. 3.

Fig. 4.

FIG. 1 is a view in perspective of a rear window for automobiles or the like showing our new design, the fragmentary portions of the automobile shown in broken lines are included for illustrative purposes only;

FIG. 2 is an end elevation thereof;

FIG. 3 is a perspective view of the rear window; and
FIG. 4 is a vertical sectional view taken along the line 4—4 of FIG. 2.

We claim:

The ornamental design for a rear window for automobiles or the like, as shown.
